PILOT-OR MASTER VALVE

Orla E. Watson, Kansas City, Mo.

Application December 4, 1944; Serial No. 566,580

3 Claims. (Cl. 137—144)

1

The present invention relates to valve construction, with particular reference to control valves of the pilot-or-master valve type, designed to regulate or control the flow through a fluid pressure line whereby the operation of other valves or pressure-regulated devices may be efficiently controlled.

Accordingly, the primary object of the invention is to provide a pilot-or-master valve having a simple and economical construction and characterized by a highly efficient and reliable operation in the carrying out of the desired control function.

As one form of construction for embodying my invention, I provide a valve casing having an interior fluid pressure chamber formed with intake and exhaust ports as well as a separate outlet for the fluid pressure control connection, together with a valve and operating means adapted to be operated in response to any suitable control means for effecting alternate opening and closing of said intake and exhaust ports.

With the foregoing general object in view the invention will now be described by reference to the accompanying drawing wherein is illustrated one practical form of construction for the suitable embodiment of my improved valve, after which those features and combinations deemed to be novel and patentable will be particularly set forth and claimed.

In the drawing, the view shown represents a sectional elevation of a pilot or master valve construction embodying the improvements of the present invention.

Pilot-or-master valves of the type to which the present invention relates and as now commonly constructed, are usually operated by float action, or in accordance with the changes in a liquid level, a float element in the vessel containing the liquid being connected with the valve for automatically operating the latter to release pressure as required for the regulation or control of another main valve, or the like, with which the pilot valve communicates through a suitable fluid pressure connection. Most of the conventional devices of this character are of a sliding valve type or involve spring toggle arrangements, and are more or less objectionable on account of being too sluggish in their action, or requiring too long an operating stroke or too great a mechanical effort for their operation.

I have sought to overcome such disadvantages by means of the construction illustrated in the accompanying drawing, which comprises a valve casing 10 providing a fluid pressure chamber 12

2

having an intake port 14 and an exhaust port 16, and also a separate and independent fluid pressure outlet 18 to be connected by any suitable pipe or the like (not shown) with the main valve or other device, the operation of which is to be controlled by the pilot or master valve.

The outlet port 18 is intended to exhaust to atmosphere, while the intake port 14 is designed to be connected with any suitable source of fluid pressure supply. These ports 14 and 16 are preferably arranged in alignment as shown, and provided with interior valve seats 15 and 17 respectively, facing toward each other and slightly spaced apart for accommodating the movements of a common valve member 20 comprising a combination valve and arm having one of its ends fulcrumed at 22 to the interior of the casing 10, and its opposite free end formed with an opening 24 for receiving the end of an operating rod or shaft 26 which is provided with spaced and rounded flanges 28 for rocking engagement with said valve arm 20.

Opposite the valve seats 15 and 17 the valve member 20 carries the valve disks 30 adapted to be brought by the movements of said member into alternate opening and closing engagement with the valve seats, as later explained.

One end of the casing 10 is provided with an extension 32 in the outer end of which is located a fulcrum 34 for the mounting of an operating lever 36, one arm of which is formed with an opening 38 for receiving the upper end of the rod or shaft 26, and said rod is also provided with a second pair of spaced and rounded flanges 28 for rocking engagement with said lever 36.

Intermediate its ends, the rod 26 is provided with a flexible diaphragm 40 of spring metal material or the like, the central portion of which diaphragm is secured by means of clamping elements 42 on said rod, while the outer margin of the diaphragm is seated and clamped against a shoulder 44 surrounding an opening 45 in the casing 10, thus forming a diaphragm chamber 46 in communication with the chamber 12, as illustrated. The diaphragm is clamped against said shoulder 44 by means of an adjustable bushing 48 which is screw-threaded into the casing above said shoulder, and within said bushing is also screw-threaded a gland element or sleeve 50 having an oversize bore for the rod or shaft 26 and also formed at its inner end with a recess 52 for seating one end of a coil spring 54, the other end of which is shouldered against the clamping element 42 at the upper or top side of the diaphragm 40, whereby the latter is actuated

by a downward spring pressure with a force dependent upon the adjustment of said sleeve 50.

The ends of the lever 36 are provided with openings 37 whereby either end of the lever may be operatively engaged with a reciprocating member or link 56, which may be connected with float-operated mechanism, in which case the member 56 may be provided with spaced shoulders 58 permitting a certain amount of play or inoperative movement as required by certain phases of the control operation, as will hereinafter appear.

When assembled for operation, the action of the spring 54 is so adjusted that it will normally overcome the spring action of the diaphragm 40, and thereby operate to maintain the valve member in closed position over the intake port 14, so long as there is no operating or lifting action exerted upon the rod or shaft 26. The adjustment of said spring action is so made, however, that an operating force, such as that of a float movement transmitted through leverage including the link 56 to the lever 36, will serve to reinforce the spring action of the diaphragm itself to an extent sufficient to lift the valve member in opposition to the spring 54 and thereby open the intake port 14 to admit the fluid pressure flow and simultaneously close the exhaust port 16. The fluid pressure is of course then transmitted through the outlet port 18 to the main valve or other device whose operation is to be controlled; and the same fluid pressure in the chamber 12 likewise maintains the diaphragm lifted against the spring 54 for keeping the port 14 open and port 16 closed until a sufficient float movement or other control action has taken place in the opposite direction, whereupon the action of said spring will be reinforced sufficiently to overcome the lift transmitted by the diaphragm element 40 and thereby reverse the valve movement, thus opening the exhaust port 16 and again closing the intake port 14. This results in release of the fluid pressure through both the pilot valve and its connection with the main valve; and obviously, this condition of the valves and relationship of parts will remain unchanged until there is again a control impulse imparted through the linkage to the rod 26, when the cycle of operation will simply be repeated.

It will therefore be apparent that I have devised a practical and highly efficient pilot valve construction for carrying out all the desired objects of my invention. It is pointed out that the intake and exhaust ports are opened wide and instantly into fully open position, and also snapped instantly into fully closed position, and that but very slight movement of the valve member is required, and that the opening and closing actions are simultaneous, as well as instantaneous in their operation. As to the degree of sensitivity of the control operation, this can be regulated to any necessary or desired extent, and made fully adequate to meet any given requirements, by appropriate adjustment of the tension of the spring 54 through the medium of the adjusting sleeve 50, as will be readily understood. Besides requiring a minimum of mechanical effort, or power, for the control operation, it is also pointed out that the action is efficient and positive, with no dead center point in the operative movements. Further advantages of the improved device are the substantially leakless char-

acter of the construction, and the fact that the same requires no lubrication in connection with its operation.

While I have illustrated and described what I now regard as the preferred form of construction for the practical embodiment of my invention, I desire to be understood as expressly reserving the right to make whatever changes or modifications may fairly fall within the scope of the appended claims.

What I claim is:

1. A master valve construction comprising a casing forming a fluid pressure chamber provided with inlet and outlet ports, a valve member operable into alternate opening and closing relation to said inlet and outlet ports, and control means for operating said valve member comprising spring-actuated diaphragm means provided with external control connections and exposed to the pressure in said chamber and acting to hold said valve member in position for normally closing said inlet port, said pressure chamber having an independent fluid pressure outlet.

2. A master valve construction comprising a casing forming a fluid pressure chamber provided with inlet and outlet ports, a valve member operable into alternate opening and closing relation to said inlet and outlet ports, and control means for operating said valve member comprising a yielding diaphragm provided with external control connections and exposed to the pressure in said chamber and operative to hold said valve member in position for normally closing said inlet port, and adjustable spring means for adjusting and regulating the action of said yielding diaphragm, said pressure chamber having a separate and independent fluid pressure outlet.

3. A pilot valve construction comprising a casing forming a fluid pressure chamber provided with inlet and outlet ports and also with an extension providing a diaphragm chamber in communication with said first chamber, a valve member operable into alternate opening and closing relation to said inlet and outlet ports, a diaphragm element mounted in said diaphragm chamber and exposed to the pressure in said first chamber, connections between said diaphragm element and valve member and operative to maintain the same in position for normally closing said inlet port, and external control means provided with connections to said diaphragm element for cooperating therewith in controlling the opening and closing movements of said valve member.
